(57) **CLAIM**

The ornamental design for a height-adjustable table, as shown and described.

DESCRIPTION

FIG. 1 is a perspective view of a first embodiment of my new design for a height-adjustable table shown at a lowered height;

FIG. 2 is a perspective view of my new design for a height-adjustable table shown at an alternate raised height; FIG. 3 is a front view of FIG. 2, wherein the opposite side of the height-adjustable table is a mirror image thereof;

FIG. 4 is a side view of FIG. 2, wherein the opposite side of the height-adjustable table is a mirror image thereof;

FIG. 5 is a top view of FIG. 2;

FIG. 6 is a perspective view of a second embodiment of my new design for a height-adjustable table shown at a lowered height;

FIG. 7 is a front view of FIG. 6, wherein the opposite side of the height-adjustable table is a mirror image thereof;

FIG. 8 is a side view of FIG. 6, wherein the opposite side of the height-adjustable table is a mirror image thereof;

FIG. 9 is a top view of FIG. 6;

FIG. 10 is a perspective view of a third embodiment of my new design for a height-adjustable table shown at a lowered height;

FIG. 11 is a perspective view of my new design for a height-adjustable table shown at an alternate raised height; FIG. 12 is a front view of FIG. 11, wherein the opposite side of the height-adjustable table is a mirror image thereof;

FIG. 13 is a side view of FIG. 11, wherein the opposite side of the height-adjustable table is a mirror image thereof;

FIG. 14 is a top view of FIG. 11; and,

FIG. 15 is an enlarged detailed view of the encircled area labeled FIG. 15 in FIG. 11.

The broken lines showing foot bases, fasteners, holes, oblique supports and locking/unlocking mechanisms shown

(Continued)

in the drawings illustrate portions of the height-adjustable table that form no part of the claimed design.
